PIN-ON FLASHLIGHT

Frank E. Gerding, Cincinnati, Ohio

Application November 30, 1949, Serial No. 6,347

Term of patent 14 years

(Cl. D48—24)

To all whom it may concern:

Be it known that I, Frank E. Gerding, a citizen of the United States, and a resident of Cincinnati, in the county of Hamilton and the State of Ohio, have invented a new, original, and ornamental Design for a Pin-On Flashlight, of which the following is a specification, reference being made to the accompanying drawing, forming a part hereof.

In the drawing:

Fig. 1 is a front elevational view of a pin-on flashlight, showing my new design;

Fig. 2 is a left end elevational view thereof.

Fig. 3 is a right end elevational view;

Fig. 4 is a rear elevational view;

Fig. 5 is a top plan view; and

Fig. 6 is a bottom plan view.

I claim:

The ornamental design for a pin-on flashlight, as shown.

FRANK E. GERDING.
